UNITED STATES PATENT OFFICE.

CHARLES W. SCHULTZ, OF DETROIT, MICHIGAN, ASSIGNOR OF TWO-THIRDS TO JAMES C. KENNEY, OF DETROIT, MICHIGAN, AND RICHARD ETHELBERT SCHULTZ, OF WINDSOR, ONTARIO, CANADA.

VENTILATING ATTACHMENT FOR WATER-CLOSET BOWLS.

SPECIFICATION forming part of Letters Patent No. 712,207, dated October 28, 1902.

Application filed June 11, 1902. Serial No. 111,110. (No model.)

To all whom it may concern:

Be it known that I, CHARLES W. SCHULTZ, a citizen of the United States, residing at Detroit, county of Wayne, State of Michigan, have invented a certain new and useful Improvement in Ventilating Attachments for Water-Closet Bowls; and I declare the following to be a full, clear, and exact description of the invention, such as will enable others skilled in the art to which it pertains to make and use the same, reference being had to the accompanying drawings, which form a part of this specification.

This invention relates to ventilators, and has for its object an improved attachment to be used especially in connection with the bowls of water-closets, for the purpose of producing a forced draft ventilation thereof.

In the drawings, Figure 1 is a side elevation showing the general arrangement of the attachment and its connection with the bowl. Fig. 2 is a longitudinal vertical section of the attachment. Fig. 3 is a cross-section at the line *x x* of Fig. 1. Fig. 4 is a perspective of the spray-rose.

A indicates the bowl of the closet, provided with the usual local vent connection 1.

The attachment comprises a tube 2, which leads from the vent-opening 1 to the vent-pipe V, leading to and through the roof. The pipe extends horizontally backward from the opening 1 to an elbow 3. From the elbow 3 a short section 4 rises vertically to the elbow 5, from which there is a horizontal connection 35 into the vent-pipe V. The pipe 2 is of comparatively large diameter, generally about two inches.

Within the pipe 2 is a second pipe 7, held in place by ring diaphragms 8 and 8^a, which, except for apertures hereinafter mentioned, extend completely across the annular chamber that surrounds the pipe 7 and is inside of the pipe 2. The pipe 7 is preferably placed near that part of the pipe 2 which lies to the top when the device is in position and at that part which lies to the bottom. There is through each diaphragm 8 and 8^a an opening which affords a passage for the return of water that has been driven longitudinally 50 through the pipe 7.

The elbow 3 is preferably made nearly rectangular and without a curve on its external or larger bend, and it is preferably lined with a cushioning metal, such as sheet-lead or some similar metal, against which water driven 55 through the pipe 7 may strike and which will deaden the sound-vibrations that would otherwise be produced by the striking of the water against the pipe or the walls of the elbow. The rectangular arrangement of the elbow is 60 to prevent the water from being directed upward or reflected upward through the pipe 4.

At that end of the pipe 2 which lies next to the bowl there is inserted through the walls of the pipe 2 an inleading water-pipe 9, which 65 has at its terminal an annular nozzle formed of two concentric pipes 10 and 11, the chamber between which is closed in at that end which lies toward the bowl and is closed at the opposite end by a piece through which 70 there are a number of very small perforations, and the nozzle thus formed throws a spray composed of a number of small streams. Through the nozzle inside the pipe 10 is an open passage-way for air, and between the 75 pipe 11 and the walls of the pipe 7 is an annular passage for air. Through the walls of the pipe 7, opposite the plate 12, are bored a number of large openings 13, through which 80 additional air may pass. These openings are 85 between the diaphragm 8^a and the bowl end of the pipe. The bowl end of the pipe is arranged to engage with the bowl in any approved way.

The pipe 9 leads from a valve-casing 14, in 85 which there is a valve 15, that preferably seats upward or with the flow of the water into the pipe 9. The valve 15 is provided with a valve-stem 16, that leads out through a suitable packing-box and is arranged to be 90 actuated by a bent lever 17, the end of which engages over a lever-arm 18, that is secured to the seat 19, the engagement being arranged and adjusted so that the last part of the seat movement toward the bowl brings the two levers 95 into engagement and actuates the valve; but the push-rod 17 and lever 18 are not in pivotal connection, and the seat may be lifted without affecting the valve 15 after the valve 15 has once reached its seat. The valve 15 100

is under tension of the spring 20, which normally tends to lift it to its seat, and it is arranged to seat with the flowing water.

The ventilating action is induced by throwing a spray of water under the hydrostatic pressure that exists in the pipe 9^a through the nozzle 12. The water thrown in a spray or in jets through the nozzle 12 carries with it the air, producing a flow of air through the pipe, and this causes an inflow into the section 2 from the bowl A and an outflow into the ventilating-pipe V, and such flow continues and rapidly removes the air that was contained in the bowl, driving the water into and through the pipe 7 and into the chamber in elbow 3, where it falls by gravity to the bottom of the pipe and runs back by gravity into the bowl.

What I claim is—

- 20 1. In a ventilating attachment for closet-bowls, in combination with a suitable casing-pipe extending from the vent of the bowl to the vent-pipe, and having in its length a horizontal portion and a vertical portion connect-
25 ed by an elbow, a spray-chamber, a return-
passage for water used for spraying purposes,
a spray-nozzle arranged to deliver a spray
into the spray-chamber, and means for con-
trolling the admission of water into said spray-
30 nozzle, substantially as described.

2. In a ventilating attachment for closet-bowls, the combination of a casing, a spray-chamber longitudinal of the casing and spaced therefrom, a nozzle-fixture arranged to admit water central to the spray-chamber, a water-
35 return channel located between the spray-chamber and the casing, and a water-gathering chamber to the end of the spray-chamber, substantially as described.

3. In a ventilating attachment for closet-
40 bowls, the combination of a casing, a spray-
chamber longitudinal of said casing, a water-
return passage parallel to said spray-chamber,
45 an annular spray-nozzle located concentric with the spray-chamber and provided with
passages central thereto and external thereto,
substantially as described.

4. In a ventilating attachment for closet-
bowls, the combination of a casing, a spray-
chamber arranged within and longitudinal of
50 the casing, a cushioning means arranged to
dampen the noise-vibrations, a return-pas-
sage for water, and a spray-nozzle, substan-
tially as described.

In testimony whereof I sign this specifica-
55 tion in the presence of two witnesses.

CHARLES W. SCHULTZ.
